UNITED STATES PATENT OFFICE.

MARTIN C. NEUNER, OF LOS ANGELES, CALIFORNIA.

SIGNATURE-REGISTER AND MACHINE-INDEX.

SPECIFICATION forming part of Letters Patent No. 595,129, dated December 7, 1897.

Application filed January 26, 1897. Serial No. 620,724. (No model.)

To all whom it may concern:

Be it known that I, MARTIN C. NEUNER, a citizen of the United States, residing at Los Angeles, in the county of Los Angeles and 5 State of California, have invented certain new and useful Improvements in a Signature-Register and Machine-Index, of which the following is a full, clear, and exact description, reference being had to the accompanying drawings, which form a part of this specification.

My invention relates to an improved device or machine whereby the operation of a key bearing a name, signature, or initial will elevate a card bearing names or signatures 10 coming under the name, signature, or initial on the key, the machine being intended more especially for the use of banks in displaying the signature of a depositor to the paying-teller, so that it may be compared with a presented check, and also as an index for book-keeping; and my invention consists in features of novelty hereinafter described and claimed.

Figure I is a perspective of my improved 15 machine, showing a bank of keys with initials thereon and with the series of name-cards placed in position in the case ready to be thrown up singly by the mechanism when the keys are depressed. Fig. II is a perspective 20 showing one of the keys depressed and the corresponding name-card elevated. Fig. III is a detail view showing the means for elevating the name-cards. Fig. IV represents a transverse section taken on line IV IV, Fig. 25 III. Fig. V represents a front elevation of one of the signature-cards and the frame in which it is supported. Fig. VI is a rear elevation of the frame for supporting the signature or name cards. Fig. VII is a transverse 30 section taken on line VII VII of the frame shown in Figs. V and VI. Fig. VIII is an enlarged detail perspective of the key-lever mechanism for raising the name or signature 35 cards. Fig. IX is a top view of one of the operating-keys. Fig. X is a section taken on line X X, Fig. III, showing the releasing-bar.

Referring to the drawings, 1 represents a case having a compartment 2 for the reception of a series of name or signature cards 3. 40 4 represents a side compartment of the case, in which are arranged rows of keys 5, each row being located at a higher altitude than the row preceding it, the keys having on their up-

per faces initials and abbreviations of words or names corresponding with the names 55 placed upon the name or signature cards. (See Figs. II and V.) The name or signature cards, in addition to having the initials of the names to be found on the card, are also divided up into spaces for the names and a 60 space in which the folio may be indicated in which the name can be found within a register or book, and also a space in which the balance remaining in bank to the credit of the person's account may be entered for the 65 purpose of giving ready information to the paying-teller.

6 represents a skeleton frame preferably formed of metal and having grooves 7 in which the name or signature cards may be 70 readily placed or withdrawn, the signature-card preferably having a metallic binding 8 on its upper edge for the preservation of the card and to afford a ready means for grasping the same when it is desired to withdraw it 75 from the frame.

9 represents a vertical bar preferably pivoted at 10, near the top of the frame, and 11 represents an arm pivoted at 12 to the lower end of the bar 9. The arm 11 is riveted at 80 30 to the inner end of a dog 13.

14 represents a link having pivotal connection at 15 16 with the dog 13 and a key-lever 17. The rear end of the key-lever 17 is pivoted at 18 to a rod 19. The keys 5 are provided 85 with stems 20, which connect said keys with the lever 17, the stems 20 being bent at 21 to a more or less degree in order to give the proper space for the keys and at the same time connect with the key-lever 17 on the 90 same line, the stems of the keys passing through the plate 22, which forms the top of the compartment in which the keys are located, and also forms a bearing to prevent sidewise movement of the keys. 95

23 represents a retaining and releasing bar which acts to hold the key in a depressed position and a signature or name card in a raised position, but which when raised up releases the parts and permits the signature 100 or name card to fall into place in the case and the key to rise up to its normal position. The release-bar is provided with slots 24, through which pins 25 project in order to guide said bar. 105

26 represents a releasing-key, preferably

having its face of different color to designate it from the card-operating keys, said releasing-key being mounted on the outer end of a key-lever 27, pivoted to the case 1 at 28 and 5 having its opposite end pivoted at 29 to the upper end of a link 31, the lower end of the link 31 being pivoted at 32 to the retaining and releasing bar 23.

33 represents a rod supported at the ends 10 of the case by suitable brackets 34. The dogs 13 are pivoted on the rod 33 and are provided on their inner face with notches 35 and overhanging lips 36. As the card-operating keys 15 are depressed (see Fig. III) the key-lever 17 causes the dog 13 to assume the position shown in dotted lines in Fig. III, at which time the retaining and releasing bar 23 drops into the notch 35 in the dog 13, thus securely holding the dog in its raised position, and with 20 it the frame and name or signature card, until such time as the operator strikes the releasing-key 26, at which time the retaining and releasing bar 23 is raised, releasing the dog 13 and permitting the name or signature 25 card and the card-operating key to return to their normal positions.

37 represents a series of grooves in the sides of the case 1, in which the ends of the frames 6 slide.

30 It will be seen that the name or signature cards may be readily changed or renewed. In arranging the operating-keys the initial letters placed thereon are arranged according to the number of names usually occurring 35 under said initials or abbreviations of words, and where names are extremely common I provide extra keys bearing said names in which the corresponding frame may receive corresponding extra cards in order to conveniently accommodate all names, be they 40 few or many.

By the means of my device a paying-teller in a bank can, by simply depressing a card-operating key, throw into elevation any signature 45 desired and compare the signature of a check with the same without having to turn to a register, and thus notifying or allowing the customer to see that he is comparing the signature. It also affords a ready machine-index displaying the name and folio whereby any desired name can be obtained in a much shorter time and with much less effort than would be the case were it necessary to turn 50 to a book with the names recorded therein.

55 38 represents projections in the frame 6 near its bottom, on which the cards 3 rest.

Having thus described my invention, the

following is what I claim as new therein and desire to secure by Letters Patent:

1. A name-register and machine-index comprising a case, a series of vertically-movable card-frames located in the case, the vertical bars pivoted to the upper part of the card-frames and on which the latter are suspended, the arms pivoted at one end to the lower ends 60 of the vertical bars, and mechanism connected with the other end of the arms for causing them to operate the vertical bars; substantially as described.

2. A name-register and machine-index comprising a case, a series of vertically-movable card-frames located in the case, the vertical bars pivoted to the upper part of the card-frames and on which the latter are suspended, the arms pivoted at one end to the vertical 70 bars, the pivoted dogs to which the other ends of the arms are secured, the retaining and releasing bar adapted to engage the dogs, and mechanism connected with the dogs for raising and lowering the arms; substantially as 75 described.

3. A name-register and machine-index comprising a case, a series of vertically-movable card-frames located in the case, the pivoted dogs having notches and overhanging lips, 80 connections between the card-frames and dogs, mechanism for operating the dogs, a retaining and releasing bar for engaging the lips of the dogs, and a key-lever and a link for operating the retaining and releasing bar; substantially as described.

4. A name-register and machine-index comprising a series of vertically-moving card-frames, vertical bars whereby the card-frames are suspended, arms pivoted at one end to the vertical bars, pivoted dogs to which the other ends of the arms are secured, key-levers, links whereby the dogs are connected with the key-levers, and rows of keys whereby the key-levers are operated; substantially as described. 100

5. A name-register and machine-index comprising a series of vertically-moving card-frames, vertical bars whereby the card-frames are suspended, arms pivoted at one end to the vertical bars, pivoted dogs to which the other ends of the arms are secured having notches and overhanging lips, key-levers, links whereby the dogs are connected with the key-levers, and a retaining and releasing bar; substantially as described. 105
